UNITED STATES PATENT OFFICE

2,672,622

DISINFECTANT ATTACHMENT FOR FLUSH TANKS

John E. Foster, Machovec, Tex.

Application October 30, 1950, Serial No. 192,841

2 Claims. (Cl. 4—227)

1

The present invention relates to new and useful improvements in flush tanks for toilets and more particularly to a disinfectant attachment for supplying disinfectant to the toilet bowl each time the bowl is flushed.

An important object of the invention is to provide a disinfectant supply tank in the flush tank of the toilet and connecting a pump to the disinfectant tank operated by the handle of the flush tank to force a regulated volume of disinfectant into the flush tank for discharge with the water into the toilet bowl.

Another object of the invention is to provide a disinfectant attachment of this character which is mounted within the flush tank and provided with a filler neck on the outside of the flush tank to replenish the supply of disinfectant without removing the top of the flush tank.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a vertical sectional view of a flush tank showing the disinfecting attachment in position therein;

Figure 2 is a top plan view with the top of the flush tank removed;

Figure 3 is an enlarged vertical sectional view taken on the line 3—3 of Figure 2;

Figure 4 is a transverse sectional view taken on the line 4—4 of Figure 3; and

Figure 5 is a fragmentary vertical sectional view of the disinfecting tank and pump showing the plunger thereof in its intake position.

Referring now to the drawings in detail, wherein for the purpose of illustration I have disclosed a preferred embodiment of the invention, the numeral 5 designates a flush tank of a type used with a toilet bowl and including an outlet pipe 6 in its bottom closed by a valve 7 and raised into its open position by a pivoted arm 8 operated by a handle 9 on the outside of the tank. The flush tank also includes the usual float 10 to control the supply of water to the tank and is otherwise of a conventional construction.

A disinfectant tank 11 is placed in the flush tank 5 to rest on the bottom of the latter and is

11 being taken downwardly from the flush tank 5 and extending outwardly from the tank 5 to the outside of the tank 5. The tank 11 is provided with a top cover 12 which is closed by a cap 13 on the outside of the tank 11. The tank 11 is provided with a pump cylinder 14 which is positioned horizontally in the lower portion of the tank 11 with the ends of the cylinder 14 projecting outwardly at opposite sides of the tank 11 and closed by caps 15 and 16. A nozzle 17 is connected to cap 16 in a position adjacent the flush tank outlet pipe 6, the nozzle including an orifice 18.

A plunger 19 is provided with a leather washer 20 having a working fit in pump cylinder 14 and a stem 21 projects rearwardly from the plunger with a flange 22 at its rear end and behind which is positioned a coil spring 23 bearing against rear cap 15 of the pump cylinder to force the plunger 19 forwardly in its pressure stroke.

Inlet ports 24 are formed in the pump cylinder 14 at a point behind plunger 19 when the latter is in its forward position to supply disinfectant from tank 11 to the pump cylinder. The top of cylinder 14 is also formed with a longitudinal slot 25 in which the lower vertical end 26 of a bellcrank lever 27 projects and which is formed at its lower end with a yoke 28 straddling the stem 21 and positioned in front of flange 22. Bellcrank lever 27 is pivoted to a bracket 29 on top of cylinder 14 and with the horizontal end 30 of the lever positioned longitudinally above the cylinder and connected to arm 8 by a rod 31 which extends upwardly through an opening 32 in the top of disinfectant tank 11.

A check valve 33 is held against a valve seat 34 in nozzle 17 by a coil spring 35 to prevent water entering the cylinder 14 from the flush tank.

In the operation of the device, flushing handle 9 is used to lift valve 7 from its seat to flush the toilet in the usual manner and as arm 8 is raised by the handle, rod 31 is also raised to actuate bellcrank lever 27 in a direction to move plunger 19 in its suction or inlet stroke, into the position shown in Figure 5. Disinfectant solution in tank 11 will then enter pump chamber 36 at the front end of cylinder 14 through the openings 24, while check valve 33 excludes the entrance of water, and when handle 9 is released spring 23 will move plunger 19 forwardly in its pressure or discharge stroke to open check valve 33 and discharge the disinfectant into the flush tank to

5 10 15 20 25 30 35 40 45 50 55

pass into the toilet bowl through outlet pipe 6.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In combination, a flush tank including a manually operated flushing mechanism, a liquid dispensing tank in the flush tank, a horizontal pump cylinder in the bottom of the dispensing tank and having one end projecting outwardly of the latter, said cylinder having an inlet internally of the dispensing tank and an outlet externally of the dispensing tank and internally of the flush tank, a pump plunger working in the cylinder, a bellcrank lever pivotally supported on the cylinder and having one end projecting laterally into the cylinder in operative engagement with the plunger and having its other end positioned outwardly of the cylinder and longitudinally with respect thereto, a pull rod connecting the said last named end of the lever to the flushing mechanism to actuate the plunger in its intake stroke, and spring means operating the plunger in its pressure stroke.

2. In combination, a flush tank including a manually operated flushing mechanism, a liquid dispensing tank in the flush tank, a horizontal pump cylinder in the bottom of the dispensing tank and having one end projecting outwardly of the latter, said cylinder having an inlet internally of the dispensing tank and an outlet externally of the dispensing tank and internally of the flush tank, a pump plunger working in the cylinder, a bellcrank lever pivoted on the cylinder and having one end projecting laterally into the cylinder and operatively engaging the plunger said lever having its other end positioned outwardly of the cylinder and longitudinally with respect thereto, a pull rod connecting the said last named end of the lever to the flushing mechanism to operate the plunger in its intake stroke, and spring means operating the plunger in its pressure stroke.

JOHN E. FOSTER.
